ATTORNEY

UNITED STATES PATENT OFFICE.

SAMUEL L. MILLER, OF CHICAGO, ILLINOIS.

CONTACT DEVICE.

Application filed June 7, 1922. Serial No. 566,663.

This invention relates to a contact device for variometers and has for its primary object the construction of a contact that has efficient operation at all times.

5 An object of the invention is the construction of a movable contact that will be positively clean at all times.

Another object of the invention is the provision of a contact that will have a cutting action so as to assure a bright surface and, therefore, a clean contact.

10 Besides the above my invention is distinguished in a contact that besides assuring a bright surface will provide a yieldable action for holding the various parts of the electrical instrument properly associated.

15 With these and other objects in view the invention will be better understood from the following detailed description taken in connection with the accompanying drawing wherein:

Fig. 1 is an end elevation of a variometer.

Fig. 2 is a vertical sectional view showing my improved contact structure in applied 25 position.

Fig. 3 is a side elevation partly in section of one of the sections.

Fig. 4 is an enlarged sectional view of a contact washer.

30 Fig. 5 is a perspective view of the stub shaft with the contact washer arranged in place.

Again referring to the drawing illustrating one of the many constructions of my invention the numerals 1 and 2 designate the 35 companion sections formed on the stator of the variometer, each recessed as indicated at 3 to snugly receive the contact plate 4. Screws 5 secure the contact plate in position and due to the countersinking of the plate, the latter is positively held against 40 loosening in the operation of the rotor 6. This rotor is supported from the contact plate by the stub shaft 7 each of which has 45 one end threaded as indicated at 8 for receiving the binding nut 9 for clamping the stub shaft to one of the terminals of the winding.

50 My contact device is in the form of a contact washer 10 that is secured to the shaft

and held against displacement by the collar 11 formed on the shaft. This contact plate is of concave convex formation so as to present a cutting edge 12 to the contact plate thereby providing a cutting action which 55 assures a clean electrical connection. To increase this action and give resiliency to the washer I form a plurality of radial slots 13 in the peripheral surface of the washer thereby forming a series of tongues 14 each 60 having individual yielding action with the contact plate. It will also be noted this construction provides a plurality of points 15 for facilitating cutting action.

From the foregoing description taken in 65 connection with the accompanying drawing it will be apparent that I provide a novel support for the rotor in combination with the novel contact device that will allow free turning of the shaft while at all times assuring excellent contact. A yieldable action 70 of the washer also assures proper positioning of the parts and smooth operation thereof.

It is, of course, to be understood that the 75 invention may be constructed in various other manners and the parts associated in different relations and, therefore, I do not desire to be limited in any manner except as set forth in the claim hereunto appended.

Having thus described my invention what I claim is:

The combination with a stud shaft having an enlarged portion formed thereon intermediate the opposite ends thereof, a collar 85 formed as a part of the stud shaft and disposed in spaced relation with respect to the enlarged portion, a conductor plate through which an end portion of the stud shaft projects, of a contact washer disposed between 90 the collar and the enlarged portion and formed substantially convex concave in shape and having a plurality of radially disposed slots formed in the peripheral edge thereof defining yieldable tongues providing 95 cutting edges adapted for cutting relation with respect to the conductor plate, substantially as described.

In testimony whereof I affix my signature.

SAMUEL L. MILLER.
